SAFETY STOP FOR BED AND CYLINDER
PRINTING PRESSES

John F. Banthin, Bridgeport, Conn.

Application November 16, 1949, Serial No. 127,706

5 Claims. (Cl. 101—278)

1

This invention relates to new and useful improvements in printing presses of the type including an impression cylinder having "on" and "off" positions and transfer means including a suction system for moving a sheet from a stack to such impression cylinder together with other transfer means for moving a printed sheet from said cylinder and has particular relation to automatic stop means for such a press.

An object of the invention is to provide in a printing press of the character outlined means for automatically and substantially instantly bringing the printing press to a complete stop on accidental loss of suction in said suction system such as may occur on failure of said transfer means to receive a sheet from said stack or on failure of such transfer means to properly hold a sheet received from the stack and on failure of the transfer means to receive a sheet from said impression cylinder, respectively.

Another object is to provide in a printing press including an impression cylinder, transfer means for moving a sheet from a stack to said cylinder and other transfer means for moving a sheet from said cylinder, means to stop said printing press on failure of said other transfer means to receive a sheet from said impression cylinder.

A further object is to provide in a printing press including an impression cylinder and a transfer means including a suction system and sucker feet for moving a sheet from a stack to said impression cylinder and a second transfer means including delivery grippers for moving a sheet from said cylinder, means for automatically and substantially instantly bringing the press to a stop on accidental failure of the suction pressure in said suction system and on failure of said delivery grippers to receive a sheet from said cylinder.

Yet another object is to provide in a printing press including an impression cylinder and means including delivery grippers for receiving sheets from said cylinder and moving them from the vicinity thereof, means for preventing damage to said press and spoilage of work by the packing of sheets about said impression cylinder due to failure of said delivery grippers to remove sheets from the vicinity of the impression cylinder.

Another object is to provide in a printing press including an impression cylinder and means including delivery grippers for receiving a sheet from said cylinder and moving the sheet from the vicinity of said cylinder, of means for automatically and substantially instantly stopping said printing press on failure of the delivery grippers

2

to receive a sheet from said impression cylinder.

A still further object is to provide in a printing press including an impression cylinder and transverse means including delivery grippers for moving a sheet from said impression cylinder of means including electromagnetic means for automatically and substantially instantly stopping said printing press on failure of said gripper fingers to receive a sheet from said cylinder, at least one of said grippers including means operable under such circumstances to close a circuit to said electro-magnetic means.

Other objects and advantages of the invention will become apparent from a consideration of the following detailed description taken in connection with the accompanying drawings wherein a satisfactory embodiment of the invention is shown. However, it is to be understood that the invention is not limited to the details disclosed but includes all such variations and modifications as fall within the spirit of the invention and the scope of the appended claims.

In the drawings:

Fig. 1 is a side elevational view showing a portion of a printing press having the present invention incorporated therein.

Fig. 2 is a side elevational view of a portion of the press shown in Fig. 1, but on a larger scale;

Fig. 3 is a further enlarged view partly in side elevation and partly in section and showing tripping mechanisms of the invention;

Fig. 4 is a top plan view of the mechanisms of Fig. 3;

Fig. 5 is an exploded view in perspective and substantially on the scale of Figs. 3 and 4 and showing the relationship of parts when the stop mechanism of the invention has been tripped;

Fig. 6 is a top plan view showing certain portions of Fig. 2 but on a larger scale;

Fig. 7 is a view looking as from the left in Fig. 6; and

Fig. 8 is an enlarged view partly in side elevation and partly in section and showing a delivery gripper of the invention.

Referring in detail to the drawings, at 10 is generally indicated a printing press and the same comprises a base or frame 11 which may be in the form of a single casting, generally rectangular in plan. Mounted on the frame 11, as by bracket or bearing means 12, is an impression cylinder 13. Operable below such impression cylinder in the usual manner is a type bed 14 adapted to be reciprocated in certain timed relation with vertical movements of the cylinder 13, 55 as is customary in the art.

At 15 is shown a support for a stack of sheets 16 of paper or other material to be printed and sheet transfer mechanism, generally designated 17, is designed for removing the sheets one at a time from the stack 16 and delivering such sheets, as removed, to the impression cylinder 13. This transfer mechanism 17 includes a pivoted arm 18 pivotally mounted as at 19 and designed to be rocked about said pivot in a path to have the transfer mechanism deliver a sheet from the stack 16 to the impression cylinder 13 and to then have a return movement to pick up the next sheet from the stack, etc.

For the operation of the transfer mechanism 17 I have shown a crank arm 20 as an extension of the arm 18 and a link 21 pivoted at its respective ends to said crank arm and a rocker 22 for rocking the transfer mechanism through the above described path of movement. Rocker 22 is pivoted intermediate its ends as at 23 and mounts a roller 24 located in a groove 25 in a cam 26 secured to a shaft 27 also having secured thereto a gear 28 meshing with a driving gear 29 on a shaft 30. This mechanism is more fully described in my application for Patent Serial No. 745,262, filed May 1, 1947.

Actually there are two of the arms 18 employed and between their upper ends they mount a manifold 31 from which flexible tubes or the like 32 connect with the vacuum suckers 33 commonly employed in the art. From a suitable source in a suction system, a suction or vacuum is applied to the manifold 31 and thence through the tubes 32 to the vacuum suckers 33. This suction is applied in certain timed relation with operations of the press, all as is usual in the art, and customarily the suction is on the suckers when they are over the stack, as in Fig. 1, whereby they pick up the top sheet from the stack.

Then, in the normal operation of this type of press, the transfer or feeding mechanism is swung forwardly about the pivots 19 until the suckers approach head stops 34 when the vacuum system is open to atmosphere whereby the vacuum suckers release the sheet against the head stops whereupon the forward edges of the sheets are engaged by the grippers (not shown) of the impression cylinder. Thereafter, return movement is applied to the transfer mechanism 17 and the vacuum suckers 33 are carried back to their loading or pick-up positions over the stack 16.

Suction to the vacuum suckers 33 originates in a vacuum pump 35 driven by a motor 36 through pulleys 37 and a belt 38. From the vacuum pump 35, a pipe 39 connects with a T-fitting 40, one branch of which mounts a vacuum gage 41 while a tube or pipe 42 from its other branch leads to a control valve device 43 which at predetermined times is maintained open to atmosphere by a latch 44 to break the suction in the system, as fully described in my co-pending application Ser. No. 29,012, filed May 25, 1948. From such control valve device, a tubing 45 connects with one end of the manifold 31 for the application of a suction thereto.

At times the vacuum suckers 33 may pick up a sheet of paper in a disarranged or inclined position whereby its forward edge is not straight across, or the suckers may drop the sheet part way to the head stops 34, or the like. Under such circumstances, the improperly placed sheet will probably get out of position in the press and later, particularly if there are several such sheets, they will become jammed about the impression cylinder

and other adjacent parts and likely result in bending or breaking or distortion of some parts.

It will be understood in this connection that prior to my invention, as disclosed in my application Ser. No. 29,013, filed May 25, 1948, if the vacuum suckers drop the sheet too soon, or in improper alignment, the operation of the press will continue and the suckers 33 of the transfer mechanism 17 will continue to shift sheets from the stack toward the impression cylinder. According to the invention of my last identified application for patent, means are provided whereby on the untimely opening of the vacuum system to atmospheric pressure, the press will be stopped almost instantly. Thus, in a press equipped with that mechanism, should one of the vacuum suckers 33 be exposed, as it will be if a sheet is held at an angle or in improper alignment, the opening of the vacuum system to atmosphere through even one vacuum sucker will cause such a drop in the vacuum pressure that the mechanism of that application will go into operation and bring about substantially instant stopping of the press.

Under such circumstances, the operator or attendant will, of course, know that something is wrong and he can then remove the improperly placed or disarranged sheet and reset the mechanism and again start the press into operation. Thus, an accumulation of sheets in positions about the impression cylinder or adjacent parts will be prevented and in this connection it will be understood that when the press is stopped by the mentioned mechanism and then again started it will continue the uninterrupted cycle so that its cycle of operation will be that for which the press was originally set.

The present invention makes use of the mechanism of my application Ser. No. 29,013 above referred to and such mechanism is herein included in combination with other safety features, all looking to a more perfect control of a printing press and to the prevention of casual damage to such a press. Thus, to the desired end, on the near side of the press frame 11 there is mounted a control box 46, the power leads to which may run through a conduit 47 and from such control box a conduit 48 carries leads to a micro switch 49 also mounted on such side of the press frame. Operation of this micro switch by means to be described results in opening of a main switch or circuit breaker or the like within the control box 46 whereby the power to the press is cut off. The operating button of the micro switch 49 is designated 50 and is shown as projected toward the delivery end of the press. This particular location is a matter of convenience.

The main drive shaft of the press 10 is designated 51 and on said shaft is a flywheel 52 and a drum 53. Shaft 51 and thus the flywheel 52 and drum 53 are driven by a belt 54 from any suitable source of power and through a belt 55 passing about a small pulley 56 fast on the shaft 51 other parts of the press may be driven. Since the drive from the shaft 51 to the various parts of the press is old and well known and conventional structure it is not deemed necessary to confuse or enlarged the present disclosure by disclosing such drive.

About the drum 53 a brake band 57 is located and the same is provided with any frictional material 58 designed to be drawn against said drum for the purpose of braking the press. One end of this band 57 is suitably anchored as at 59 to a side wall 60 of the frame 11 while the other end

of the band is anchored as at 61 to an arm 62 of a lever generally designated 63. Intermediate its ends this lever is pivotally mounted at 64 and then the second arm 65 of the lever is carried upwardly and at its upper end is provided with a laterally extending lug 66, the purpose of which will appear. Also, at its upper end the lever is provided with a projection or extension 67 constituting a hand piece for use in rocking the lever.

A coil spring 68 anchored at one end to the frame wall 60 as at 69 has its other end anchored to a stud 70 rigid with the lever arm 65 toward the upper end of the latter. Clearly, the spring 68 is constantly tending to rock the lever 63 about the pivot 64 in a counterclockwise direction and in a direction to tighten the brake band 57 about the drum 53 to draw the friction pad or lining 58 of such brake band into tight engagement with the drum whereby to provide a braking action for the whole press.

Pivotedly mounted on the frame wall 60, as by a stud 71, is a trigger device generally designated 72 and in side elevation generally of inverted T formation. Thus, the trigger 72 comprises a generally vertical arm 73 comprising the stem of the T and a pair of oppositely extending generally horizontal arms 74 and 75 together comprising the head of the T. A short stud or shaft 76 on the trigger arm 75 mounts a roller 77 designed to engage and press inwardly on the operating stem or button 59 of the microswitch 49 whereby to trip said switch, as will appear.

Trigger arm 74 is laterally thickened and enlarged on its inner side toward its free end and is provided with a notch 78 designed to substantially receive or to receive a substantial part of the enlargement, projection or protuberance 66 at the upper end of the lever arm 65 when the trigger 72 is functioning to retain the lever 63 in a brake release position against the tendency of the spring 68 to move said lever to a brake applied position.

Extending outwardly from the near side of the stem 73 of the trigger 72 is a short projection or stud 79 comprising a finger or hand piece for convenient use in manually rocking said trigger for the resetting of the present mechanism, as will presently appear. In its inner side, at its upper end, the trigger arm or stem 73 is laterally enlarged providing a shoulder or surface 80 designed to be engaged by a projection or pin 81 of a trip mechanism generally designated 82 at predetermined times, as will be set forth.

The trip mechanism 82 is more particularly shown, or is better shown, in Figs. 3 and 4 of the drawings. There it will be seen that such mechanism includes a bracket 83 secured to the side 60 of the press 10 as by bolts 84 passing through openings 85 in a thickened or pad-like portion 86 of said bracket. In addition to said pad-like portion, the bracket includes a forwardly extending elongated arm 87 and an upstanding rigid lug-like portion 88 at right angles to the arm 87 and located approximately at the juncture of said arm and the pad-like portion 86 of the bracket.

Toward its forward end the bracket arm 87 mounts a stud 89 projecting from the inner side of said arm and passing through a lever 90 intermediate the ends of the latter but in eccentric relation to the mid point thereof. Thus, in the drawings, the stud 89 is located forwardly of the mid portion of the lever 90 whereby said lever is overbalanced toward its rear end and its rear portion or its portion to the right of the pivot 75

89 (Figs. 3 and 4) overbalances the lever portion to the left of said pivot. Therefore, the lever under the influence of gravity constantly tends to move to and below the full line position of Fig. 3 in a clockwise direction or in a direction to carry its forward or shorter end portion upwardly.

Extending laterally from the inner side of the forward end portion of the lever 90 are a pair of studs 91 and 92 passing through slots 93 and 94, respectively, in the elongated body portion 95 of a dog 96 which at its forward end is provided with an upstanding tooth 97 straight at its inner side whereby to provide a shoulder or contact part 98. The pin 81 above referred to is shown as extending entirely through the body 95 of the dog 96 and includes a portion 99 projecting at the inner side of such body. Anchored at one end to this pin portion 99 is a relatively heavy coil spring 100 which at its other end is anchored to a stud 101 projecting from the inner side of the lever 90.

With this construction, spring 100 is constantly tending to close and therefore is constantly drawing inwardly on the dog 96 in a manner to bring the body portion 95 of said dog into overlapping relation with the forward end portion of lever 90. Thus, the spring 100 tends constantly to maintain the dog 96 and the lever 90 in such relation that the studs 91 and 92 are always in the forward end portions of the slots 93 and 94, respectively. From the foregoing it will be seen that the lever 90 constitutes a primary member of the trip mechanism and the dog 96 constitutes a secondary member.

As will later appear, the trip mechanism 82 and particularly the dog 96 thereof, cooperate with a pawl or dog actuating part 102 mounted at the near side and toward the forward edge of the bed 14, as on a stud or the like 103. The mounting and purpose of the pawl 102 will later be fully set forth but here it is noted that the pawl is located laterally of one edge of the type bed 14 and that such pawl includes an arm 104 and a head 105, the latter including a straight or flat forward surface 106 and a bevelled or inclined lower surface 107. It will be understood that during use of the press, and in each cycle of the press operation, the type bed 14 is moved through a complete reciprocation. That is, it is moved first in one direction and then in the opposite direction under the cylinder 13.

As the type bed moves toward the feeder end of the press (that end of the press supporting the stack of sheets 18) the bevelled or inclined surface 107 of the pawl 102 may ride over the bevelled surface of the tooth 97 should the latter be in the path of movement of the pawl and then under certain predetermined conditions, as will be described, when the bed moves in the opposite direction as the dog 96 is in the position shown in full lines in Fig. 3 its shoulder 98 will be engaged by the straight or flat surface 106 of the pawl 102 and the dog will be drawn forwardly a predetermined distance with the type bed 14 to bring about movement of the trigger 72 and release of the lever 63, all as will be more particularly set forth.

A wing-like arm 108 is secured as by bolts 109 to the lug or upstanding extension 88 of the bracket 83 and such wing serves to support a body 110. This body 110 is provided with a cylindrical chamber 111 opening through its lower end and through a lateral orifice 112 communicating with a passageway 113, in turn communi-

cating with a port or lateral opening 114 in which is threaded one end of a tube or pipe 115. Such tube or pipe 115 is, through a piece of flexible tubing or the like 116, in communication with the manifold 31. Extending through the lower open end of the chamber 111 is a cylindrical plunger 117 at its lower end provided with a bifurcated head 118 shown as straddling the longer end portion of the lever 90 and secured thereto by a cross pin 119 passing through the lever and the arms of the bifurcated head 118. This pin 119 is rigid with the head 118 but passes through an elongated opening 120 in the lever 90 for a certain relative movement of these parts, as will be clear. In addition to the head 118, the plunger 117 includes a cylindrical portion 121 slidably in the chamber 111 and open at its inner end.

An adjusting screw 122 enters the chamber 111 through the upper end of the body 110 and within such chamber engages a sleeve 123, which sleeve is of a diameter to telescopically enter the inner or open upper end of the cylindrical portion 121 of plunger 117. This latter plunger may be described as spring loaded since a coil spring 124 is located within such plunger and the inner end portion of sleeve 123 and at one end bears against a part of said sleeve and at its other end against the head 118 of the plunger. Clearly, this coil spring tends to project the plunger from the chamber 111 and to resist slight movement of the plunger into said chamber.

At its upper end, screw 122 is provided with a knurled head 125 for use in adjusting the screw and a lock nut 126 is provided for securing the screw in adjusted positions and against casual movement relative to the body 110. This screw is adapted for adjustment to move the sleeve 123 longitudinally of the chamber 111 to vary the pressure of the spring 124 on the plunger head 118. The bracket arm 87 is provided with an opening 127 and the longer arm portion of lever 90 is provided with an opening 128. It will be clear that through the tube 116 the vacuum or suction system connected with the vacuum suckers 33 is also connected with the chamber 111 and when vacuum is applied to this system and the same is closed to atmosphere the suction resulting in the chamber 111 draws the plunger 117 inwardly of such chamber rocking the lever 90 to the dot and dash line position of Fig. 3. In this position of the parts, the hole 128 aligns with the hole 127.

When setting up the press and timing it, the lever 90 may be manually rocked to this dot and dash line position and then a cotter pin or the like, as shown at 129 in Fig. 4, is passed through the aligned holes to maintain the lever 90 and the dog 96 in the dot and dash line operating position while the press is being timed and is manually operated through its normal cycle. When the press is in use, the cotter pin or other means 129 is removed from the openings 127 and 128 and the latter have no function. That is, this cotter pin 129 and these holes 127 and 128 are only used in set-ups or for adjustments of the press to prevent the present stop means from acting while the press is being manually moved through its cycle and testings for necessary adjustments or for other set-up purposes.

In the operation of the press 10, the transfer mechanism 17, vacuum being present in the described system when in the position of Fig. 1, through its vacuum suckers 33 takes the top-most sheet from the stack 16. At this time, the impression cylinder 13 is in its upper or "off"

position. Through conventional press mechanism, the transfer means is shifted and delivers this sheet to the head stops 34 to be engaged by the gripper buttons (not shown) of the impression cylinder 13.

At the time of the delivery of a sheet to the impression cylinder, the vacuum system is open to atmosphere as by means disclosed in my application Ser. No. 745,262, breaking the suction on the vacuum suckers 33 whereby to have the latter release the sheet. As the transfer mechanism returns toward the stack 16 the cylinder 13 is lowered to "on" position and the bed 14 carries the type under the cylinder and into engagement with the sheet on the latter whereby such sheet is printed. This is conventional. At this time, the vacuum system is closed to atmosphere and so there is a suction through the manifold 31 and the tube 116 and tube 115 to the chamber 111 and the plunger 117 is in its inner or upper position and the lever 90 is in the dot and dash line position of that figure. Thus, as the bed 14 moves, the surface 107 of the pawl 102 will not strike the dog but will merely pass above the same.

Now, on failure of vacuum in the vacuum system as, for example, if one of the vacuum suckers 33 is exposed to the atmosphere because a sheet is not properly held or is not sealing such vacuum sucker, the vacuum fails or at least falls in the chamber 111 and the plunger 117 moves downwardly allowing the lever 90 to drop or pivot to its full line position of Fig. 3. As this occurs, the lever 90 carries the dog 96 to the full line position of the latter in said figure. Now, as the bed 14 continues movement toward the left in Fig. 3, the surface 106 of the pawl 102 will engage the shoulder 98 of the tooth 97 of dog 96 in a manner to move or drag said dog toward the left with such movement of the type bed. Such movement of dog 96 is possible against the resistance of the spring 100 and results in some elongation of said spring. However, as the dog is so moved, it moves relative to the lever 90 since the latter is mounted on the stud or pivot 89 and is not capable of longitudinal movement.

The slots 93 and 94 receiving the studs 91 and 92 permit of longitudinal movement of the dog 96 relative to the lever 90. However, it is noted that the slots 93 and 94 incline upwardly toward one another so that their inner or adjacent end portions are higher than their outer or remote end portions. Thus, as the dog 96 is moved by the pawl 102, the dog not only moves outwardly or toward the left in Fig. 3 but its front or toothed end portion 97 also must move downwardly. The pins and slots cause a cam-like action.

As the dog so starts to move, the pin or projection 81 of the dog is bearing against the shoulder or surface 80 of the stem 73 of the lever or trigger 72. Thus, this lever or trigger must rock in a counterclockwise direction. As it so rocks its roller 71 swings upwardly and depresses the microswitch actuator 59 opening the power circuit of the press by the tripping of a switch or circuit breaker or the like in the control box 46. This cuts off the power to the press.

Additionally, the described movement of the trigger 72 carries the shoulder or notch 78 of the outer end portion of its arm 74 downwardly releasing the lug or lateral extension 66 at the upper end of the arm 65 of lever 63. Immediately such lug 66 is released the spring 68 rocks the lever 63 in a counterclockwise direction about the pivot 64 tightening the brake band 57 and drawing its frictional lining 58 tight against the drum 53

whereby a braking action is applied to the power shaft 51.

At this time, it will be understood that power has been cut off by interruption of the circuit in the primary motor and the application of the brake as described results in the whole press being rapidly brought to a standstill.

When the dog 96 reaches the dot and dash line position of Fig. 3 it will be clear that the pawl 102 may then pass over the dog so that there will be no damage to any part. Further, it will be clear that the pin 81 of the dog need only cause over-balancing of the trigger 72 to carry the notch 78 of the latter downwardly sufficient to release the extension 66 of the lever 63. Immediately this is done, the brake is applied and immediately prior to such operation the roller 77 has actuated the control element 50 of the microswitch. Thus, if the vacuum suckers 33 are not all sealed by a sheet being transferred, or if they are carrying no sheet, the press is stopped so that investigation may be made as to the improper operation of the press before any damage is caused.

Thus, according to the present construction herein disclosed, the transfer mechanism 17 cannot be delivering sheets at an angle or in the wrong way to the impression cylinder so as to clog up the press or cause other trouble. Unless the transfer means is operating properly, the vacuum in the vacuum system fails and the plunger 117 drops resulting in movement of the dog 96 to the full line position of Fig. 3 where such dog will be engaged by the pawl 102 and the trip device 82 is moved to open the power circuit to the press and to admit of application of the braking mechanism.

After the operator has remedied any defects and removed any misplaced sheets or the like, he draws the lever 63 to brake release position by using the handle 67 and actuates the trigger 72 back to set position with its recess 78 receiving the lug or extension 66 of the lever 63 and with the surface 88 of said lever adjacent the pin 81. In this connection, it will be understood that immediately the press is tripped the dog 96 has been moved to the broken line position of Fig. 3 and the straight edge 106 of the pawl 102 passed over the tooth 97 of the dog so the latter has been freed and by the spring 100 is immediately returned to its normal position awaiting the resetting of trigger 72 and the lever 63.

The described means operates to stop the printing press without destroying the established cycle of operation of the latter. Therefore, when a difficulty has been remedied the operator merely resets the trigger 63 and the press starts up at any place in its established cycle at which place it was stopped. Further, the press mechanism is effective to automatically stop operation of the press after the last sheet has been fed or transferred from the stack 16 to the impression cylinder 13. At such time when the vacuum suckers 33 are returned to the feeder table, there is no sheet for them to pick up or to seal them and thus the vacuum system remains open to atmospheric pressure through the vacuum suckers 33 and the present mechanism is set into operation and the entire press brought to a standstill.

The pawl 102 in the present disclosure is replacing the plate 79 of my application Ser. No. 29,013 and in the present disclosure has a function in addition to its function already described herein. This separate function is to operate the above described trip mechanism on the failure of delivery grippers to receive or to remove a sheet

from the impression cylinder 13. It will be understood that should the transfer mechanism 17 continue to deliver sheets to the impression cylinder and should the proper portions of the press fail to remove such sheets from the impression cylinder, a number of the sheets will become wedged and press about and under the cylinder resulting in damage to the press and costly work spoilage. Thus, I have provided means for setting the above described tripping mechanism into operation to open the power circuit of the press and to apply the brake on failure of transfer means, including delivery grippers for removing sheets from the impression cylinder, to receive during any cycle of the machine's operation, a sheet from such cylinder.

This second transfer means I have generally designated 130 and the same includes a frame structure including an upright 131 shown on the inner side of the machine 10 and a similar upright (not shown) opposite upright or bracket 131. These uprights or brackets are fastened to and movable with the type bed 14 and between their upper ends support bar 132 (see Figs. 6 and 7) along which at the desired spaced intervals are mounted the desired number of delivery grippers, of which but two are shown, being generally designated 133 and 134, respectively. The delivery gripper 134 may be of the exact construction as that disclosed in my application Ser. No. 729,492, filed February 19, 1947 (now Patent No. 2,509,030 of May 23, 1950), while the delivery gripper 133 has been slightly modified.

This delivery gripper is shown alone in Fig. 8 and therein comprises a frame generally designated 135 and which is blanked and formed from sheet metal as, for example, steel. The frame 135 is elongated and is transversely U-shaped. Thus, the frame comprises a pair of side walls 136 and 137 and a bottom wall 138. In their forward portions the side walls are relatively shallow and together with the forward portion of the bottom wall define a channel 139 in which are mounted a gripper shoe 140 and a gripper finger 141.

Bottom wall 138 has the major portion of the gripper shoe thereagainst and such shoe is secured in place as by rivets 142 passing through an inner portion of the shoe and said bottom wall. The forward end portion 143 of the shoe extends forwardly of the frame 135 and is curved slightly upwardly as shown. In their forward end portions, the side walls 136 and 137 are bent inwardly as at 144 and then outwardly providing wing-like portions 145, as is customary in the art.

The gripper finger 141 is located above the shoe 140 and is pivotally mounted as on a short shaft or bar 146 supported in the frame side walls 136 and 137. Pivot pin or bar 146 is of steel and is chrome plated for long wear. A spring 147 includes a pair of eye portions 148 located about the shaft 146, one at each side of the finger 141, and further includes arms 149 and a bight portion 150, the latter being disposed under the inner end of the gripper finger 141. In addition, spring 147 includes arms 151 the free end portions of which bear against the bottom wall 138.

With this construction, it will be clear that the spring 147 is constantly urging the gripper finger 141 about the pivot 146 in a direction to have the forward lower bevelled surface 152 of such finger in engagement with or tending toward engagement with the projecting end portion 143 of the gripper shoe 140. However, it will be clear that the proper pressure on the inner end portion of the gripper finger 141 will overcome the spring

147 and result in the finger being rocked to carry its forward end upwardly away from the shoe.

Rearwardly of the gripper finger 141 the side walls 136 and 137 of the frame 135 are widened or heightened providing relatively deep sides or portions 153. A slot 154 is provided in the side wall portions and enters from the rear ends thereof and extends to a point spaced a slight distance rearwardly from the rear end of the gripper finger 141. Extending continuously about said slot 154 is an angularly related flange 155, which flange serves to very materially strengthen the frame structure at this point. Slot 154 is of reduced width in its inner end portion and preferably terminates in an arcuate end 156 for engagement with a portion of the surface of a cam shaft or gripper finger operating means 157.

In its larger rear portion, the slot 154 is designed to receive the supporting bar 132 and preferably at this portion the slot is carried inwardly or restricted as at 158 so that such restricted portions are engaging the outer forward portion of the bar 132 when the frame 135 is mounted on the latter and cam shaft 157. The continuous flange 155 bears against the bar 132 and the shaft 157 whereby the latter are not engaged merely by the edges of the side wall portions of the frame but are engaged over a substantial area. It is noted that the supporting bar 132 and the cam shaft or gripper finger operating means 157 are in substantially parallel relation.

A rivet or other means 159 is used to mount or secure a double nut 160 against the underside of the rearward portion of the bottom wall 138 of the frame 135. Substantially aligned with the nut 160 but straddling the upper edges of the rearward portions of the side walls of the frame is a lock cap 161. This cap comprises an upper wall portion 162 extending over the upper edges of the side walls of frame 135 and further includes side portions 163 disposed at the outer sides of the upper edges of said side walls. In addition, lock cap 161 includes end flanges 164 located between the side wall portions of the frame at the respective ends of the top wall portion 162 of said lock cap.

When a delivery gripper is to be mounted on the supporting bar 132 and the cam shaft 157, the gripper is simply moved in the direction of its length after aligning its slot 154 with such bar and shaft whereby to dispose the latter in the illustrated positions of Fig. 8 within said slot. Thereafter, bolts 165 are passed downwardly through the wall 162 of the lock cap and at each side or preferably in engagement with the bar 132. These bolts are then threaded into tapped holes provided in the double nut 160. If desired, spring lock washers 166 are placed under the heads of said bolts.

The supporting bar 132 being mounted by the upper ends of the brackets 131 and the latter being mounted by the type bed 14, it will be clear that said supporting bar as well as the various delivery grippers mounted thereon and the cam shaft 157 will move with the type bed and thus will be carried forwardly toward the impression cylinder 13 and rearwardly therefrom. Additionally, the cam shaft 157 is adapted for rocking or oscillating movement, as is old in the art.

The cam shaft is operated in timed relation with other operations of the press, as is the practise in the art, to rock the gripper finger 141 to the position of Fig. 8 against the tendency of the spring 147 and to release the gripper finger for movement by said spring whereby to have the 75

forward end portion of the gripper finger move to or toward gripping relation with the upper surface of the inclined portion 143 of the gripper shoe 140. To the desired end, a collar 167 is mounted on the cam shaft 157 and is located between the side walls of the frame 135. This collar carries a radially projected pin 168.

As the bar 132 and shaft 157 are moved forwardly carrying the delivery grippers, cam shaft 157 is oscillated to rock its collars 167 and the pins 168 are carried downwardly against the rear portions 169 of the gripper fingers 141 rocking the latter on their pivots 146 to the position of Fig. 8. Thus, after the proper forward movement, a sheet 15 of paper or other material is received from the impression cylinder between the open ends of the shoe 140 and the fingers 141, as between the end 143 of the shoe and the surface 152 of the finger.

Then the cam shaft is rocked in the opposite direction carrying the pin 168 away from the inner or rear end of the finger 141 whereupon the spring 147 acts to rock the finger back towards a gripping relation with the shoe. Thereafter the shaft 152 starts rearwardly, the received sheet is shifted rearwardly, and at or toward the end of the stroke the cam shaft is again rocked or oscillated to have the pins 168 of the various grippers rock the fingers 141 of the latter against the tendency of the springs 147 so as to have the fingers release the sheet. At such time, as is customary in the art, the released sheet is received on belts or conveyors 170 supported as by bracket 171 and located immediately below the path of movements of the grippers.

35 The particular gripper 133, as above mentioned, is of slightly modified construction. Preferably, this gripper is the middle gripper of those mounted on the supporting bar 132. The modification consists in a slight change or addition in the gripper finger 141. For the present purpose, an opening is formed through the forward end portion of said finger and in such opening there is located a tubular insulator 172 through which extends a lead 173, the conductor 174 of which is electrically connected with a button-like contact or head 175 located at the lower side of the lower bevelled surface portion 152 of the gripper finger.

Lead 173 (see especially Fig. 6) is carried rearwardly with respect to the gripper finger 133 and through a hole 176 is carried into the supporting bar 132 and extends entirely through the same to the inner end thereof and where it emerges from the shaft or bar it is identified as 177. The lead is secured against an upright or bracket 131 by a clamp 178 and is electrically connected with a magnet or solenoid 179 mounted against the outer side of said bracket. From such solenoid or magnet 179 a lead 180 extends to a spring pressed ball contact 181 suitably mounted on a part of the type bed 14 as in a block of Micarta or other insulating material 182. It will be clear that the ball contact 181 together with the magnet or solenoid 179 and the other electrical parts thus far described all move as a unit with the delivery grippers and the type bed.

60 Bolts 183 (Figs. 6 and 7) extending from the inner side of the frame wall 60 mount a plate-like support 184, the same being held in spaced relation to the wall 60 as by collars or spacers 185 located about the bolts 183. This support or plate 184 is of electrically insulating material. On the upper edge of the support 184 is a conductor 186 in the form of an L-shaped strap. Such conductor has one arm extending across the upper edge of the support 184 and the other arm

against the side of said support and is clamped in place as by a strap 187. A bolt or binding post 188 anchors the upper end of a lead 189 electrically with the conductor 186 while its lower end is connected with a transformer 190 clamped onto brackets 191 supported on the inner side of the wall 60. A second lead 192 from the transformer 190 is grounded on one of the brackets 191 as at 193 (Fig. 6). The supply line to the transformer is illustrated at 194.

It will be understood that the transformer being grounded to one of the brackets 191, the latter being secured to the wall 60 of the machine frame or base, that the transformer is grounded. Further, it will be apparent that the gripper shoe 140 of the delivery gripper 133 is grounded as through the frame of the gripper and the supporting bar 132 and brackets 131 and the type bed, etc, to the frame of the press.

Except when the delivery grippers are in their forward positions to receive a sheet from the impression cylinder 13, the ball contact 181 is spaced rearwardly from the elongated track-like contact 186. This is clear from Fig. 6. However, when the delivery grippers are moved forwardly or are in their forward positions, such as positions in which they are to receive a printed sheet from the impression cylinder 13, the ball contact 181 is on the elongated track-like contact 186. At this time, the circuit from one side of the transformer is grounded on the frame of the press and from the other side of the transformer the circuit is through lead 189 to contact 186 through ball contact 181 to lead 180 through the solenoid or electro magnet 179 and lead 177 plus lead 173 to the contact button 175 on the underside of the finger 141. The transformer 190 is a step-down transformer and the voltage from the transformer is very low as, for example, about 12 volts.

Thus, the circuit at the time indicated being as above described, the only thing needed to close the circuit is for the contact button 175 to engage the upper side of the inclined portion 143 of the gripper shoe 140. As has been indicated, but a very low voltage is being used and when the cam shaft 157 is reversed to release the gripper finger 141 of delivery gripper 133, the spring 147 rocks such finger into gripping position and a piece of paper or the like is clamped between the forward portion of the gripper finger and the portion 143 of the gripper shoe. The di-electric properties of even a sheet of paper are sufficient to insulate the gripper finger and the gripper shoe and no circuit is closed through the solenoid or electro magnet 179. Under such circumstances, the operation of the machine continues through its normal cycle.

However, if the delivery gripper 133 fails to receive a sheet of paper or the like from the impression cylinder, contact button 175 directly engages the upper surface of the inclined portion 143 of the gripper shoe 140 and a circuit is closed through the solenoid or electro magnet 179. When this occurs, the pawl 102 is rocked from the position of Figs. 1 and 2 to the position of Fig. 3. The result of such movement will later be set forth in detail but now it is though best to consider the manner in which the closing of the circuit brings about this movement of the pawl. Thus, a core 195 is moved upwardly when the solenoid or electromagnet 179 is energized. This core at its lower end is rigidly secured to a pin 196 extending inwardly through a slot 197 in the tail end portion 104 of the pawl 102. This pin

and slot connection between the core 195 and the pawl 102 is necessary since the core has a straight vertical movement and the pawl must rock about the pivot 103.

When the magnet or solenoid is energized, pawl 102 is rocked in a counterclockwise direction about the pivot 103 and such movement is limited by a stop pin 198. Then when the magnet or solenoid is de-energized (this being its normal condition during normal cycle of the machine's operation), core 195 drops downwardly and the pawl 102 rocks in a clockwise direction on the pivot 103 and such movement of the pawl is limited by a stop pin 199. This movement to normal position of the pawl is solely under the influence of gravity since the core plus the tail portion of the pawl is of sufficient mass to overbalance the head portion of the pawl as the latter is mounted on the stud or pivot 103.

During the normal cycle of the machine's operation, transfer means 17 delivers a sheet to be printed to the impression cylinder and retreats to take another sheet from the stack 16 and a printing cycle is performed and the printed sheet 20 is taken from the impression cylinder by the delivery grippers and carried rearwardly and delivered onto the belts 170 which carry the printed sheet away. A preferably transparent piece 200 disposed over the roller 201 keeps the newly printed sheet from contact with the latter or any adjacent parts. In this connection, it will be understood that the grippers are gripping one edge portion of the sheet, i. e., its lead edge portion, and that otherwise the sheet is not supported by the grippers and that its trailing edge would drag onto the roller 201 or onto adjacent parts except for the presence of protecting sheet 200.

After the grippers deliver a sheet onto the belts 170 they are returned toward the impression cylinder to receive the second sheet therefrom. Thus, the two transfer means 17 and 130 operate in timed relation with operation of the impression cylinder and the type bed, etc. As long as the two transfer means are operating properly, the present stop means does not function and is merely "stand by."

On failure of the transfer means 17 to receive a sheet from the stack 16, or if a sheet is not properly received as, for example, if it is at an angle or the like so that one of the vacuum suckers 33 is not sealed by the sheet, the suction pressure fails in the vacuum system and the plunger 117 drops permitting the lever 90 to move about the pivot 89 from the dot and dash line to the full line position of Fig. 3. This carries the dog 96 upwardly as to the full line position of Fig. 3 and even though the pawl 102 is in its normal position (solenoid or magnet 179 not being energized) the lower portion of the forward surface 106 of the pawl will engage the surface 98 of the dog and drag the same forwardly tripping or releasing the trigger 72 and bringing about opening of the power circuit of the press and the application of the brake band 57 to the drum 53 to bring the press to a stop.

Of course, at this time, pawl 102 stays in its normal position since now all the power to the press is cut off. In this normal position of the pawl, as long as the dog 96 is held in its normal position for operation of the press, the pawl will not engage the latter. Further details of the stopping of the press on failure of vacuum in the suction system has previously been given and it

is believed that angle of the disclosure has been sufficiently covered.

As has been previously suggested, if the transfer means 17 is continuously delivering paper or other material to be printed upon to the impression cylinder and such material is not being carried from the impression cylinder by the transfer means 103, the material will pack about the impression cylinder and it has happened that this material is so tightly packed and compressed that adjacent portions of the machine have been broken. Such feed of sheets to the impression cylinder and failure of removal of the sheets from such cylinder also results in spoilage of work, perhaps in a run of expensive stock. This may occur where the operator moves from one machine to another or otherwise leaves an operating machine being satisfied that there is an ample supply of sheets in the stack 16. The means by which the machine is stopped on failure of the transfer means 130 to remove a sheet from the vicinity of the impression cylinder will now be described.

Should the grippers be in their forward positions, a low voltage circuit is closed with the exception of the slight gap between the contact button 175 at the underside of gripper finger 141 and the upper side of the angular or bent portion 143 of the gripper shoe 140. Now, if the gripper fails to receive a sheet from the impression cylinder and the cam shaft 157 operates in its usual cycle so that the gripper finger 151 is released to the action of the spring 147, the contact button 175 is moved against the gripper shoe 140 closing the above mentioned low voltage circuit.

That circuit includes the solenoid or magnet 179 and the latter being energized the pawl 102 is rocked to the position of Fig. 3. In this position of the pawl the lower portion of its flat forward face 106 will engage the surface 98 of the tooth 97 of dog 96 even though such dog is in its normal position being held there by the lever 90 which is in its normal position, wherein it is supported by the plunger 117 due to the presence of suction in the vacuum system of the transfer means 17.

As the pawl engages the tooth 97 in the manner described, the dog 96 is drawn forwardly against the tendency of the spring 100 and the projecting end portion of the pin 81 riding against the surface portion 80 of trigger 72 rocks the same in a counterclockwise direction causing its roller 77 to depress the actuator 50 of the micro switch 49 to bring about opening of the power circuit of the press. Further, the slight movement of the trigger 72 in the direction indicated carries its shoulder or surface 78 from in front of the extension 66 of lever 63 whereby the latter is released to movement under the influence of the spring 68 and the brake applied to the drum 53 as previously set forth. This brings the entire press to a stop.

The operator then understands the reason why the grippers have not received a sheet from the impression cylinder, makes any corrections or adjustments necessary and then moves the brake lever 63 to release the brake and resets the trigger 72 to hold the brake in "off" position and the cycle of the machine's operation may be continued on reclosing of the necessary switch. In this connection, it will be understood that when the power to the press was cut off, the low voltage to the magnet or solenoid 179 was cut off so that the pawl 102 has returned to its normal position, as in Figs. 1 and 2.

Having thus set forth the nature of my invention, what I claim is:

1. In a printing press including an impression cylinder, a first transfer mechanism for transferring sheets from a pile to said cylinder, said transfer mechanism including a suction system, a second transfer mechanism for transferring sheets from said cylinder, said second transfer mechanism including a delivery gripper and means for moving the same toward said cylinder to receive a sheet and to then move the delivery gripper from the cylinder to carry the received sheet from the vicinity of the cylinder, an electric power circuit, a switch controlling said power circuit, means for applying a braking action to a given part of the press, a trigger having a normal position maintaining said braking mechanism inoperative, means mounting said trigger for movement from said normal position to a released position to release said braking mechanism, said switch positioned to be engaged and operated by said trigger as the latter moves from its normal to its released position, a trip mechanism including a mounting bracket secured on the press, a substantially horizontal lever pivoted intermediate its ends to said bracket, a substantially vertical body on said bracket and having a cylindrical recess opening through its lower end, a plunger including a portion in said recess and a head at the lower end thereof and connected with one end portion of said lever, a pair of studs extending substantially horizontally from one side of the other end portion of said lever, a dog comprising an elongated body portion against said side of said end portion of said lever and extending beyond the outer end of said end portion of the lever and having an upstanding tooth on its portion beyond said end portion of the lever, said dog having a pair of slots through said body portion and through which said studs extend, a spring anchored at one end to said dog and at its other end to said lever and normally urging said dog toward a retracted side-by-side relation with said end portion of said lever whereby the dog is located with the studs in the forward ends of the respective slots, said slots inclining from their outer toward their inner or adjacent ends whereby said dog is normally held by said spring in a position with its toothed portion extending upwardly at an incline and whereby on said dog being moved forwardly to a projected position relative to said lever said studs will be in the relative portions of said slots and said dog body will be substantially parallel with said lever, said cylindrical recess connected in the vacuum system of said first transfer mechanism whereby when said system is filled said plunger is drawn into said recess, said plunger when drawn into and held in said recess holding said lever in a position with said dog substantially horizontal, a part movable with a movable part of the press and adapted to engage and shift said dog to projected position against the tendency of said spring, said dog adapted when shifted to projected position to engage and move said trigger from its normal to its released position to open said switch and release said braking mechanism for braking action on said given part of the press, said plunger while in said cylindrical recess and under the control of the suction of the suction system of the first mentioned transfer mechanism supporting said lever in a position maintaining said dog out of the path of movement of said part movable with a moving part of the press and adapted on failure

of suction in said suction system to be released to permit of rocking movement of said lever whereby to carry said dog into a position to be engaged by said part movable with a moving part of the press, said part movably mounted on said moving part of the press and normally positioned to pass by said dog when the latter is in its first mentioned position, and means under the control of said delivery gripper of the second transfer mechanism for moving said part into position to engage said dog when the latter is in its first mentioned position on failure of the delivery gripper to receive a sheet from said impression cylinder.

2. In a printing press including an impression cylinder, a transfer mechanism for transferring sheets from a pile to said cylinder, a second transfer mechanism for transferring sheets from said cylinder, a frame, a bed reciprocable on said frame beneath said cylinder, power means, control means operable to control said power means whereby the press is started and stopped, trigger means for effecting the operation of said control means, and a trigger tripping mechanism comprising a primary member movably mounted on said frame for movement from a normal position to a moved position, means under the control of one of said transfer mechanisms for moving said primary member into its moved position on failure of said transfer mechanism to transfer a sheet, a secondary member movably mounted on said primary member for movement from a normal position to a moved position in which latter position it actuates said trigger means in control operating direction, an actuating part for said secondary member movably mounted on said reciprocating bed for movement from a normal position to a moved position, a contact part on said secondary member arranged to be contacted by said normally positioned actuating part as it reciprocates in the direction of the trigger actuating direction of movement of said secondary member, said contact part being out of the path of said normally positioned actuating part in the normal position of said primary member and being moved into said path in the moved position of said primary member, and means under the control of the other of said transfer mechanisms for moving said actuating part, on failure of said other of said transfer mechanisms to transfer a sheet, into position to engage said contact part when said primary member is in its normal position.

3. In a printing press including an impression cylinder, a transfer mechanism for transferring sheets from a pile to said cylinder, said transfer mechanism including a suction system, a second transfer mechanism for transferring sheets from said cylinder, said second transfer mechanism including a delivery gripper and means for moving the same toward said cylinder to receive a sheet and from said cylinder to carry the received sheet therefrom, a frame, a bed reciprocable on said frame beneath said cylinder, power means, control means operable to control said power means whereby the press is started and stopped, trigger means for effecting the operation of said control means, and a trigger tripping mechanism comprising a primary member movably mounted on said frame for movement from a normal position to a moved position, vacuum operated means under the control of said suction system of said first transfer mechanism for moving said primary member into its moved position on failure of suction in said suction system, a secondary

member movably mounted on said primary member for movement from a normal position to a moved position in which latter position it actuates said trigger means in control operating direction, an actuating part for said secondary member movably mounted on said reciprocating bed for movement from a normal position to a moved position, an electromagnet operable upon being energized to move said actuating part from its normal to its moved position, a circuit for said electromagnet, a contact part on said secondary member arranged to be contacted by said normally positioned actuating part as it reciprocates in the direction of the trigger actuating direction of movement of said secondary member, said contact part being out of the path of said normally positioned actuating part in the normal position of said primary member and being moved into said path in the moved position of said primary member, and means whereby on failure of said delivery gripper of said second transfer mechanism to receive a sheet from said impression cylinder said circuit is closed to energize said electromagnet to move said actuating part into position to engage said contact part when said primary member is in its normal position.

4. In a printing press including an impression cylinder, a transfer mechanism for transferring sheets from a pile to said cylinder, said transfer mechanism including a suction system, a second transfer mechanism for transferring sheets from said cylinder, said second transfer mechanism including a delivery gripper and means for moving the same toward said cylinder to receive a sheet and from said cylinder to carry the received sheet therefrom, a frame, a bed reciprocable on said frame beneath said cylinder, power means, control means operable to control said power means whereby the press is started and stopped, trigger means for effecting the operation of said control means, and a trigger tripping mechanism comprising a lever pivotally mounted on said frame intermediate the ends of said lever, a vacuum operated plunger in communication with said suction system connected with one arm of said lever and adapted to draw said arm in one direction while vacuum is applied to said plunger whereby the other arm is moved in the opposite direction, lever actuating spring means arranged to move said lever in the opposite direction upon failure of the vacuum, a dog, means mounting said dog on said other arm of said lever for swinging movement therewith and for longitudinal movement thereon from a normal position, spring means exerting longitudinal force in one direction on said dog to return it to normal position from a longitudinally moved position, trigger actuating means on said dog arranged to move said trigger means in control operating direction through longitudinal movement of said dog in opposition to said last mentioned spring means, a dog actuating pawl movably mounted on said reciprocating bed for movement from a normal position to a moved position, a pawl engaging part on said dog arranged to be contacted by said normally positioned pawl as it reciprocates in the direction of the trigger actuating direction of longitudinal movement of said dog, said pawl engaging part being out of the path of said normally positioned pawl in the vacuum moved position of said lever and being moved into said path by said lever actuating spring means upon failure of said vacuum, and means under the control of said delivery gripper of the second transfer mechanism for moving said pawl into

position to engage said pawl engaging part of said dog, when said lever is in its vacuum moved position, on failure of the delivery gripper to receive a sheet from said impression cylinder.

5. In a printing press including an impression cylinder, a transfer mechanism for transferring sheets from a pile to said cylinder, said transfer mechanism including a suction system, a second transfer mechanism for transferring sheets from said cylinder, said second transfer mechanism including a delivery gripper and means for moving the same toward said cylinder to receive a sheet and from said cylinder to carry the received sheet therefrom, a frame, a bed reciprocable on said frame beneath said cylinder, power means, control means operable to control said power means whereby the press is started and stopped, trigger means for effecting the operation of said control means, and a trigger tripping mechanism comprising a lever pivotally mounted on said frame intermediate the ends of said lever, a vacuum operated plunger in communication with said suction system connected with one arm of said lever and adapted to draw said arm in one direction while vacuum is applied to said plunger whereby the other arm is moved in the opposite direction, lever actuating spring means arranged to move said lever in the opposite direction upon failure of the vacuum, a dog, means mounting said dog on said other arm of said lever for swinging movement therewith and for longitudinal movement thereon from a normal position, spring means exerting longitudinal force in one direction on said dog to return it to normal position from a longitudinally moved position, trigger actuating means on said dog arranged to move said trigger means in control operating direction through longitudinal movement of said dog in opposition to said last mentioned spring means, a dog actuating pawl
